EYEGLASS TEMPLE

Avis Jean Coval, Dayton, Ohio, assignor to The Univis
Lens Company, Dayton, Ohio, a corporation of Ohio

Application June 13, 1957, Serial No. 46,578

Term of patent 14 years

(Cl. D57—1)

FIG-1

FIG-4

Fig. 1 is an elevational view of an eyeglass temple embodying the original and ornamental design;

Fig. 2 is a plan view of the eyeglass temple of Fig. 1;
Fig. 3 is a sectional view along line 3—3 of Fig. 1; and
Fig. 4 is a sectional view along line 4—4 of Fig. 1.

The drawing shows the left temple, and the right temple is the mirror image thereof.

I claim:

The ornamental design for an eyeglass temple, substantially as shown and described.
